UNITED STATES PATENT OFFICE.

FRANZ A. BLOCKI, OF SHEBOYGAN, WISCONSIN.

SILO.

Application filed April 30, 1923. Serial No. 635,528.

To all whom it may concern:

Be it known that I, FRANZ A. BLOCKI, a citizen of the United States, residing at Sheboygan, county of Sheboygan, and State of Wisconsin, have invented new and useful Improvements in Silos, of which the following is a specification.

This invention relates to improvements in silos.

10 It is the primary object of this invention to provide a novel form of silo which can be erected by a single workman without requiring the exercise of unusual strength. In an ordinary frame silo construction the 15 uprights or posts of the silo are unitary and are handled with difficulty by a single workman. In fact, it is frequently impossible for a single man to construct a silo of the ordinary construction. This invention 20 contemplates the provision of uprights or posts which are fabricated by the workman as he proceeds with the erection of the structure and it is my object to provide a fabricated post which will have all of the 25 strength of a solid post and will also be adapted to co-operate with the sheathing to produce an unusually substantial structure. In attaining this object, it is my desire to provide posts or uprights extending from 30 bottom to top of the silo.

Further objects of this invention are to provide a silo, the uprights of which can be constructed from small pieces of material which might ordinarily be considered as 35 waste; to provide a silo of a type utilizing pre-formed pieces which can readily be assembled by an inexperienced man; and to provide a silo in which the external sheathing is held together in a manner obviating 40 the necessity for using hoops or bands.

In the drawings:

Figure 1 is a fragmental view in perspective of the wall of a partially erected silo constructed in accordance with this invention.

Figure 2 is a horizontal section through a fragment of the wall shown in Figure 1.

Figure 3 is detail view in perspective of a silo post or upright fabricated in accordance with this invention.

It will be noted that the silo disclosed herein is a frame structure having uprights or posts which are designated in their entirety by the reference character 5 and are 55 connected by inner sheathing 6 and outer sheathing 7. The whole structure is pref-

erably erected upon a base or foundation 8 to which the uprights 5 are preferably secured by means hereinafter to be described.

Frame silos have ordinarily been constructed heretofore with one piece uprights extending from bottom to top of the silo. Where such a silo is of any considerable size, the erection of an upright of sufficient strength to withstand the pressure of the silo contents requires great skill and a great expenditure of effort. It is ordinarily necessary for a number of men to assist in the erection of an integral upright member of the type referred to. The present invention 70 contemplates the use of fabricated uprights to which sections may be added as the structure increases in height. It is thereby made possible for a concern engaged in the manufacture of silos to standardize members intended for use in this manner so that, regardless of the height of the silo which it is purposed to build, the structural elements entering into the building can all be of equal dimensions. To produce a structure 80 of increased height, it is only necessary to use an additional number of the structural elements which enter into the fabrication of the uprights.

In the preferred embodiment of this invention, which is herein disclosed, each upright or post 5 is made up of a plurality of comparatively short blocks 9 and 10 which are assembled in staggered relation so that the abutting surfaces of each pair of blocks 90 10 will lie intermediate the ends of a block 9. Similarly, the abutting ends of each pair of blocks 9 will lie intermediate the ends of a single block 10. The blocks 9 and 10 are similar and each is preferably so formed 95 that its inner face 11 is shorter than its outer face 12. Thus when blocks 9 and 10 are assembled, in the manner clearly shown in Figure 3, the outer faces 12 of the several blocks 9 will lie in a plane at an angle to 100 the plane which includes the corresponding faces 12' of the several blocks 10. This angle will be determined by the number of sides which it is purposed to form in the silo.

The blocks 9 and 10 may be secured together in any desired manner, but for convenience in erection and for permanence, they are preferably bolted together as indicated in the accompanying drawings. Each block may 110 be conveniently provided with four bolt holes extending transversely therethrough.

The bolts 14 will be passed through said holes in a manner such that each block will be secured by two of said bolts to each of two adjacent blocks.

5 Although the blocks 9 and 10 may be bolted directly together with mutually overlapping joints, I nevertheless prefer to interpose between them a plain strip 15 which may conveniently be termed "an abutting strip," since it projects at 16 and thereby provides a shoulder against which the boards comprising the inner sheathing 6 may abut.

It is immaterial to this invention whether the strip 15 is made up of sections breaking 15 joints with blocks 9 and 10, or whether the strip 15 is continuous from top to bottom of the silo. At the right in Figure 1, an abutting strip 15 is shown to be horizontally divided at 17, the upper part of said strip 20 having been superimposed on the lower part thereof during the fabrication of the upright. However, it is sufficiently light so that it will require the exercise of no considerable power in its erection if it is erected 25 to full height in one piece.

In order to complete the post or upright 5 at its top and bottom, half blocks 9' and 10' are used in the manner best shown in Figure 3. Each of such blocks will be held 30 in place by two of the said bolts 14.

A securing member 18 is held to each upright 5 by the lower two bolts 14 thereof. If the foundation 8 be made of concrete, or the like, the extremity of the securing member 18 may be embedded therein. If a wooden foundation be used, the member 18 may bend, as indicated in dotted lines in Figure 3, to provide a right angle bracket which may be bolted to the foundation. In either case, the same securing bolts 14 which 40 secure blocks 9 and 10' together serve the added function of connecting to the upright 5 the member 18.

As has previously been indicated, the silo 45 walls will preferably comprise the inner and outer sheathing 6 and 7. The boards comprising the inner sheathing will, due to the shape of the silo, and to the interposition of the portions 16 of each strip 15, necessarily be shorter than those boards which make 50 up the outer sheathing 7. The boards of the sheathing will be disposed with their ends abutting the strips 15 and will be nailed or otherwise secured to the inner surfaces 11 55 of the blocks 9 and 10. The boards which make up the outer sheathing 7 will preferably have their respective ends in mutually abutting contact, as indicated in Figure 1, and will be nailed, or otherwise secured, to the outer surface 12 of blocks 9 and 10. Inasmuch as the blocks are securely bolted together, the two sets of sheathing will be able 60 to withstand considerable bursting strain without further securing means.

65 As an additional precaution, however, I

prefer to use the plates 20 which overlap the joints between the abutting ends of boards comprising the outer sheathing 7. These plates 20 are provided with suitable openings to receive nails, screws, or bolts 70 which pass through such boards into the blocks 9 and 10 respectively. The use of the plates absolutely prevents any separation of the boards which comprise the outer sheathing and thereby makes the use of 75 hoops or bands about the silo unnecessary.

The construction herein disclosed will 80 recommend itself to those skilled in the art as being unusually easy of assembly and also unusually rigid when complete.

I claim:

1. A silo, including an upright structural member comprising a plurality of units secured together, an interposing strip between said units and having a portion extending 85 beyond the faces of said units whereby the said member may be assembled during the erection of the silo instead of being initially raised to its full height.

2. A silo, including an upright structural 90 member comprising a plurality of units disposed in two series in mutually overlapping relation and having a strip interposed between them and extending across the overlapping portions of said series.

3. A silo, including an upright structural member comprising a plurality of units disposed in two series in mutually overlapping relation, the intermediate units of each series being each secured to a plurality of units of 100 the other series.

4. A silo, including a fabricated upright structural member comprising two series of mutually overlapping units, a strip interposed between the units of said series and 105 extending unbroken past a plurality of units of each series, and means for securing together in assembled relation the units of said series and the interposed strip.

5. A silo, including a fabricated upright 110 comprising a plurality of units disposed in two series, the ends of said units in each series being mutually overlapped with the ends of units in the other series, an interposed strip between said series of units having a marginal portion extended outwardly 115 beyond the faces of the units, whereby an abutting shoulder is formed, and means for securing said units and interposed strip together.

6. A structural upright for building, said upright comprising a plurality of similar units disposed in two series, the units of one series being symmetrically overlapped with respect to the units of the other series, and 125 securing bolts fastening each intermediate unit to two units of the other series.

7. A silo including a plurality of fabricated uprights, each composed of similar units disposed in two series in mutually 130

overlapping relation, each of said units being formed to provide an outer face wider than its inner face, an abutting strip interposed between the series of units and breaking joints with the units of each series, a plurality of securing bolts holding each intermediate unit to two units of the other series and to the abutting strip, together with inner sheathing boards secured to the smaller faces of said units and abutting 10 said strip, and outer sheathing boards secured to the outer faces of said units.

FRANZ A. BLOCKI.
